UNITED STATES PATENT OFFICE.

WILLIAM B. BESSEY, OF ELMIRA, NEW YORK.

CAR-COUPING.

SPECIFICATION forming part of Letters Patent No. 285,787, dated October 2, 1883.

Application filed May 26, 1882. (No model.)

To all whom it may concern:

Be it known that I, WILLIAM B. BESSEY, a citizen of the United States, residing at Elmira, in the county of Chemung, and in the 5 State of New York, have invented a certain new and useful Improvement in Car-Couplings; and I do hereby declare that the following is a full, clear, and exact description of the invention.

10 The object of my invention is to furnish a device whereby cars may be coupled together with ordinary links without danger to the persons in charge of the work of coupling the same. I attain this object by means of the 15 mechanism shown in the accompanying drawings, in which—

Figure 1 is a longitudinal section of a draw-head, showing all the parts of the device. Fig. 2 is a cross-section, and Fig. 3 is a plan.

20 In the drawings, *a* is the hinged draw-bar. *b* is a supporting-dog pivoted to a draw-bar. *c* is an arm at nearly right angles to and rigidly attached to *b*, for the purpose of throwing the latter forward when lifted out of its 25 mortise. *d* is the portion of the bottom of the chamber upon which *b* will rest when the draw-bar *a* is lifted and the link withdrawn. *e* is the hinge where the draw-bar *a* is attached to the tail of draw-head. *f* is an ordinary 30 link. *g* is the draw-head.

It will be seen that the pin is connected with the hinged draw-bar in such a manner that when the pin is lifted, either by taking hold of the head of it with the hand from 35 above or by means of a chain extending to any desired point above—as, for instance, the top of a box-car—the hinged draw-bar and supporting-dog are also lifted, and the arm *c* being heavy and eccentric to the pivot by 40 which *b* is connected with draw-bar *a*, *b* will be thrown forward and rest upon *d*. In this position it will remain till tripped by forcibly inserting a link, when it will again resume the position shown in Fig. 1.

45 It will also be seen that when, in coupling cars, an ordinary link is inserted in one draw-head in the manner shown in Fig. 1, (it may be a straight or crooked link, owing to whether the cars be of same or different heights,) and the pin is lifted, so that the dog *b* will rest 50 on *d*, the coupling will be accomplished by simply running the cars together, even in the absence of an attendant.

The dog *b*, being pivoted to the draw-bar *a* at its upper end, and having its lower end 55 always in position to be forced against the back wall of the mortise in the lower draw-bar, forms a stop to prevent the link being forced at any time too far back into the chamber between the draw-bars.

60 By a proper adjustment of all the parts the cars may be coupled closely, as in passenger-coaches, or loosely, as in freight-cars, so that without dispensing with the favorite and time-honored link-connection, I have thus 65 produced a device most simple and effective for coupling cars of any description, whereby entire convenience and safety are secured.

It will be seen that the draw-bar *a* in my 70 device is not merely a factor in a pin holding and tripping device; but is, in fact, to all intents and purposes, a draw-bar and pin combined, and as a draw-bar entirely fills the office of the stationary upper draw-bar in common use. The draw-bar *a* is kept from being 75 lifted too high by the stop *m* of the buffer-head, so that when properly adjusted the dog *b* cannot be lifted out of the mortise in the lower draw-bar.

The pin *h* may be rigidly fastened in the 80 draw-bar *a* or loosely, whichever may be preferred; but if loosely, then a collar, *k*, will be required.

What I claim as new, and desire to secure by Letters Patent, is—

85 1. In a car-coupling, the combination of the upper draw-bar and its coacting coupling-pin *h* and dog *b*, with the lower draw-bar, by means of a hinge or its equivalent, at any point forward of the swivel-head, in such 90 manner as that, when the pin is lifted, the draw-bar is also lifted and held up by the dog *b*, substantially as and for the purposes set forth.

2. The combination, with the upper draw-bar, *a*, connected with the lower draw-bar by means of a hinge or its equivalent, and having the pin *h* securely fastened thereto, of a

dog, *b*, having an eccentric arm, *c*, and a shoulder, *l*, substantially as and for the purpose set forth.

3. The combination of the upper and lower draw-bars, the pin *h*, the dog *b*, the draw-head, and the link *f*, whereby the link *f*, when forced against the dog *b*, with its shoulder *l* resting on *d*, trips it and causes the fall of the upper

draw-bar, *a*, and the pin *h*, and is itself not only engaged by the pin, but is firmly clamped to between the upper and lower draw-bars, and thus held in horizontal position.

WILLIAM B. BESSEY.
